BAG FRAME

William C. Hiering, Millburn Township, N. J., assignor to J. E. Mergott Company, Newark, N. J., a corporation of Delaware

Application November 16, 1932
Serial No. 642,858

4 Claims. (Cl. 150—29)

This invention relates to hand bags, and more particularly to improvements in frames used in such bags.

The attaching of bag material to frame members usually requires considerable time and labor, and accordingly increases the cost of manufacturing a hand bag. A number of expedients have been devised, to facilitate the attaching of bag covering material to frame members, but they 10 necessitate the use of relatively expensive frame members, which again increases the cost of manufacturing.

It is therefore an object of this invention to provide a relatively inexpensive and simple bag frame device to which bag covering material can be conveniently and readily attached with a minimum of labor and time.

A further object is the provision of a frame for hand bags which requires the attaching of 20 bag covering only to the longitudinal portions of the frame members.

These and other advantageous objects, which will later appear, are accomplished by the simple and practical construction, combination and arrangements of parts hereinafter described and shown in the accompanying drawing, forming part hereof, and in which:

Fig. 1 is a perspective view of a handbag embodying my invention,

30 Fig. 2 is a perspective view of the handbag showing the manner in which the bag covering material is attached to a frame,

Fig. 3 is a view of a corner of a frame member showing the manner of attaching the longitudinal portion to the legs of the frame member,

35 Fig. 4 is a view, partly in section, showing in detail the manner of attaching the covering material to the longitudinal portion of a frame member.

40 Referring to the drawing, there is shown a hand bag having side walls 5, and gussets 6 connecting the side walls at the ends of the bag. The upper edges of the side walls extend above the upper edges of the gussets 6 and each wall 45 has attached to the upper edge thereof a metal strip, which preferably is a metal channel 7, as shown in Fig. 2.

The bag frame is shown to comprise a pair of U-shaped frame members, each member having bowed legs 8, preferably made of wire rod, the adjacent legs of the frame members being hingedly connected at 9. The legs are substantially straight at the upper ends and bowed at the lower ends, so that when the frame members 55 are latched the adjacent legs 8 produce substan-

tially a pear shape, which gives the desired spreading or bulging to the lower portion of the hand bag.

Each frame member has a longitudinal portion having a vertical wall 10 with an outwardly directed horizontal upper flange 11, the lower edge of the wall 10 having, preferably, a pair of spaced bendable tabs 12 although any number of tabs or other securing means can be used. The upper ends of the legs 8 are split and receive 60 the ends of the flange 11 (see Fig. 3) which is fixed to the legs by soldering or similar means.

Suitable latching means 13 are mounted on the flanges 11.

70 The covering material is readily and conveniently attached to the frame members by placing the channels 7, which are crimped to the covering material, against the wall 10, as shown in Fig. 4, and then bending the tabs 12 up to clamp the channels securely in place.

75 It will be noted that the legs 8 are in no way attached to the bag covering material, and obviously the upper edges of the walls 5 can be stiffened by other means than the channels, such as metal strips, or equivalent means.

80 From the above description, it will be seen that I have provided a simple bag frame device of great strength and a minimum number of parts, to which bag covering material can be quickly attached merely by clamping the channels 7, or metal strips, attached to the covering material, to the walls 10, and no further operations are necessary.

85 The foregoing disclosure is to be regarded as 90 descriptive and illustrative only, and not as restrictive or limitative of the invention, of which obviously an embodiment may be constructed including many modifications without departing from the general scope herein indicated and denoted in the appended claims.

95 Having thus described my invention, what I claim as new and desire to secure by Letters Patents, is:

1. A hand bag frame, comprising a pair of 100 hingedly connected members, each of said members having a pair of legs and a longitudinal portion fixed to one of the legs, said legs being substantially straight at the end adjacent the longitudinal portion and bowed outwardly at the opposite end, the adjacent legs of the members being in the same plane and having their straight portions abutting when the longitudinal portions of the members are brought together and means carried by the longitudinal portion to secure bag 105 covering material thereto.

2. A hand bag frame, comprising a pair of hingedly connected members, each of said members having a pair of legs and a longitudinal portion connecting the legs, said legs being substantially straight at the ends adjacent the longitudinal portion and bowed outwardly at the opposite end, the adjacent legs of the members being in the same plane.
3. In a hand bag having side walls of bag covering material, stiffening means attached to the upper edges of the side walls, a pair of hingedly connected bag frame members, each of said members having a pair of legs and a longitudinal portion attached to the legs, said legs being substantially straight at the end adjacent the longitudinal portion and bowed outwardly at the opposite end, the adjacent legs of the members

being in the same plane, the longitudinal portion comprising a wall having an outwardly directed right angular flange, said stiffening means being positioned against said wall below the flange, and means on the wall to securely hold the stiffening means and bag covering material against the wall.

4. In a hand bag frame, comprising a pair of hingedly connected members, each of said members having a pair of legs, said legs having a straight portion at one end and an outwardly bowed portion at the other end, the adjacent legs of the members being in the same plane, and means attached to the straight portions of the legs of each member for holding bag covering material.

WILLIAM C. HIERING.
